UNITED STATES PATENT OFFICE.

FRIDTJOF NIELSEN BRONDBY, OF CHRISTIANIA, NORWAY, ASSIGNOR TO A/S PERKUSSION, OF CHRISTIANIA, NORWAY.

COMBINED RIFLE GRENADE AND HAND GRENADE.

1,416,545.

Specification of Letters Patent. Patented May 16, 1922.

Application filed March 2, 1920. Serial No. 362,668.

To all whom it may concern:

Be it known that I, FRIDTJOF NIELSEN BRONDBY, a subject of Norway, and a resident of Christiania, Kingdom of Norway, 5 have invented certain new and useful Improvements in Combined Rifle Grenades and Hand Grenades, for which I have filed an application in Norway dated Feb. 1, 1919, and of which the following is a specification, 10 this application being a continuation in part of application Ser. No. 285,976, filed May 29, 1919, and renewed as application Ser. No. 362,740 on March 2, 1920.

This invention relates to grenades and the 15 object of the invention is a grenade which explodes upon striking, no matter in which position it strikes, and which may according to the circumstances be used either as a hand grenade or as a rifle grenade, or if 20 desired as the projectile of a bomb thrower.

My grenade possesses great advantage in 25 that it may be shot from a rifle by means of ordinary rifle ammunition. It also satisfies the other requirements of an ideal grenade.

According to my invention the grenade 30 ordinarily embodies a central tube which permits passing of the rifle bullet without damaging the ignition mechanism or the charge of the grenade. The ignition mechanism and charge are placed around the central tube. My grenade is preferably of a form which fits well in the hand. It weighs about 500 grams. Size, form and weight 35 may, however, be varied as desired. If the grenade is to be used only as a hand grenade the central tube is not necessary and may be omitted; and the construction of the ignition mechanism may be varied accordingly 40 as will readily be understood by those skilled in the art. The grenade is absolutely safe during transport, and is provided with means for inserting the detonator separately.

In the illustrative drawings which form 45 a part of this application Figure 1 is a longitudinal section of the grenade;

Fig. 2 is a similar section of the grenade in a different plane from Fig. 1 illustrating the detonator;

Fig. 3 is a side elevation of the grenade 50 showing in longitudinal section a casing and mounting used in connection with firing from a rifle;

Fig. 4 is a side elevation of the grenade 55 provided with the casing and mounting illus-

trated in Fig. 3 and showing the end of a rifle barrel;

Fig. 5 is a longitudinal section broken away of the grenade showing a part of the casing and mounting for use in connection 60 with rifles and illustrating a modified arrangement of auxiliary propeller charge; and

Fig. 6 is a longitudinal section of a modification of the grenade of Fig. 1 illustrating the omission of the central tube therefrom and the detonator centrally positioned 65 in the grenade, as well as other modifications later to be referred to.

Referring more particularly to the construction of Figs. 1 and 2 the central tube has slidably mounted thereon a cylindrical body 1, which is provided at its forward end with a flange 3 and is normally maintained in a rearward position of safety by 70 means of a suitably mounted spring 2. A detonating needle 4 is conveniently mounted on the forward face of the flange in a position on forward movement thereof to explode a percussion cap 13 carried at the 75 rear of a removable detonator 14. The detonator is intended to be placed in the grenade when the latter is to be launched and is thereafter maintained therein in explosive relation with the charge 15 of the 80 grenade. The rear end of the cylindrical body is bevelled for engagement with the pointed end of a release safety pin 11 normally held in engagement therewith by means of a sleeve 12 provided with a suitable 85 means for disengagement therefrom, such as a cord. When thus disengaged the pin will be moved outwardly on forward movement of the cylindrical body by the bevelled end thereof, thus releasing the latter for firing movement.

An actuating member 6 of conical form is mounted on the cylindrical body 1. The forward end of the actuating member is provided with a flange 7 for co-action with the flange 3 of the cylindrical body. The rear portion of the actuating member is provided with a loose bearing on the cylindrical body, and the actuating member is constructed and mounted in such manner that 10 both reciprocating movement thereof and a generally transverse movement of the flange 7 in relation to the cylindrical body 1 are provided for.

A link may be provided between the flange 11

3 of the cylindrical body and the flange 7 of the actuating body. Such a link is here illustrated as comprising balls 8, 8 mounted in oppositely disposed curved recesses in the 5 respective flanges.

The actuating member is weighted by means of an annular weight 9 slidably mounted thereon and is normally maintained in cooperative relation with the cylindrical body by means of a spring 10 interposed between the weight and the base of the grenade, which spring is normally not under compression.

When the grenade is to be launched from a rifle it is provided with a metal casing 17 the forward end of which is penetrable by the rifle ball, and at the rear of which a suitable mounting is attached in line with the central tube for fastening to the forward end of the rifle barrel illustrated at 19 (see Figs. 3 and 4). An auxiliary propelling charge ignitable by the powder gases escaping from the muzzle of the rifle barrel may if desired be provided, and is illustrated as pressed into an annular groove 20 formed on the base of the grenade. Suitable means are provided for disengaging the safety sleeve 12 from the safety pin 11 on launching the grenade from the rifle.

My grenade will act in the following manner: At the moment when the grenade is launched the sleeve 12 is removed by means of the cord. As my grenade is not provided with a steering tail, it will turn in all directions during its flight, and striking may take place in the following positions:

(1) Point down, (2) base down, (3) on the side, (4) in an intermediate position.

In the first case the impact of the annular weight 9 will act on the actuating member 6, further on the steel balls 8 and the flange 3 and finally on the detonating needle 4, which will be pressed into the percussion cap 13. Thereby the detonator 14 is ignited and consequently the charge 15 will explode.

In the second case the impact of the annular weight will compress the spring 10, which on recoiling will hurl the weight back, and ignition and explosion will take place as in the first case.

In the third case, by side striking, the annular weight will together with the actuating member act as a pendulum and swing to one side, the flange 7 moving in a generally transverse direction. The steel balls together with the curved recesses in which they are placed will then act as a wedge and displace the cylindrical body in longitudinal direction in such manner that the detonating needle is pressed into the percussion cap with resulting explosion of the grenade.

In the fourth case, the grenade striking in an intermediate position, a combination of

the above described actions will take place, and cause explosion of the grenade.

When the grenade is to be launched from a rifle and is provided with the casing as above described, it is placed upon the forward end of the rifle barrel and the rifle fired. The powder gases escaping from the muzzle of the rifle barrel project the grenade in the direction of firing and cause the same to burst through the forward end of the casing. In addition the escaping powder gases ignite the auxiliary propelling charge heretofore referred to as being located in the groove 20, which of course increases the projecting effort on the grenade. It is estimated that the shooting range of the grenade may be increased to 400 meters in case the said propelling charge is employed. The explosion of the grenade will obviously take place in the same manner as above described.

It is not thought necessary to dwell at length upon the modifications of the grenade illustrated in Figs. 5 and 6. In Fig. 5 the auxiliary propelling charge instead of being located in an annular groove is shown as carried by a hollow cylinder 21. In Fig. 6 the intermediate link comprising the balls 8, 8 of Fig. 1 is omitted and the flanges 3 and 7 are conical in a direction toward the base of the grenade, the cone of the flange 3 being slightly more obtuse than that of the flange 7 and the flanges normally being in contact one with the other. Furthermore in Fig. 6 the central tube of Fig. 1 is omitted and is replaced by the tube carrying the removable detonator 14. This being centrally located, the detonating needle is accordingly mounted at the center of the flange 3.

The foregoing detailed description of my invention has been given for clearness of understanding, and no undue limitation should be deducted therefrom, but the appended claims should be construed as broadly as permissible in view of the prior art. It will be noted that I have in my prior application Ser. No. 269,164, filed December 31, 1918, disclosed and claimed firing mechanism suitable for use in a grenade, embodying a weighted actuating member and a firing member with a driving connection between the two comprising enlarged heads, the actuating member being mounted for swinging movement, and a firing spring holding the actuating member towards the firing member.

What I claim as new and desire to secure by Letters Patent of the United States is:

1. In a grenade, the combination of a sliding firing member provided at one end with a flange, and an actuating member therefor comprising a body portion loosely surrounding and capable of transverse movement in respect to the firing member and having a flange co-acting with the flange on the firing

member on firing, whereby a transverse movement of the flange on the actuating member effects a longitudinal movement of the firing member.

5. 2. In a grenade, the combination with a detonator of a sliding firing member therefor comprising a body portion provided at one end with a flange, an actuating member therefor having a body portion loosely surrounding and longitudinally and transversely movable on the body portion of the firing member and having the flange co-acting in the firing with the flange of the firing member whereby a transverse movement of the flange on the actuating member effects a longitudinal movement of the firing member, a weight surrounding the actuating member, a spring normally holding the weight toward the flange of the last 15 named member and a spring normally holding the firing member away from the detonator.

3. In a grenade, the combination of a central tube, a firing mechanism comprising a cylindrical body longitudinally slidable on said tube and provided at one end with a flange, and a weighted actuating member therefor having a flange surrounding the tube and capable of transverse movement in 25 respect to the tube and co-acting in the firing with the flange on the cylindrical body, whereby a transverse movement of the flange effects a longitudinal movement of the cylindrical body, substantially as described.

4. In a grenade, the combination of a central tube, a firing mechanism comprising a cylindrical body longitudinally slidable on said tube and provided at one end with a flange, an actuating member therefor also 40 slideable on the tube and having a flange capable of transverse movement in respect to the tube and co-acting in the firing with the flange on the cylindrical body whereby a transverse movement of the flange effects a longitudinal movement of the cylindrical body, a weight slideable on the actuating member, and a spring normally pressing the weight towards the flange on the cylindrical 45 body, substantially as described.

5. In a grenade, the combination of a slideable cylindrical body provided with a flange, a conical actuating member surrounding the cylindrical body and longitudinally and 55 transversely movable in respect thereto, the actuating member being also provided with a flange, and means for transferring a swinging movement of the actuating member to a longitudinal movement of the cylindrical 60 body.

6. In a grenade, the combination of a central tube throughout the length of the grenade, a cylindrical body slideable on said tube and provided with a flange, a conical actuating member outside the cylindrical body lon-

gitudinally and transversely movable in respect thereto, the actuating member being also provided with a flange, an annular weight on the actuating member, a spring holding the weight tight on the actuating member, and means for transferring a swinging movement of the actuating member to a longitudinal movement of the cylindrical body.

7. In a grenade, the combination of a central tube throughout the length of the grenade, a cylindrical body slideable on said tube and provided with a flange, a swinging and sliding conical actuating member outside said cylindrical body also provided with a flange, an annular weight on the actuating member, a spring holding the weight tight on the actuating member, the respective flanges being provided with oppositely disposed recesses, and balls located in the said recesses, the flange on the actuating member and the balls acting as a wedge on a swinging movement of the actuating member and transferring said movement to a longitudinal movement of the cylindrical body.

8. In a grenade, the combination of a central tube throughout the length of the grenade, a cylindrical body slideable on said tube and provided with a flange, a spring for normally maintaining the cylindrical body in a position of safety, a detonating needle operatively associated with the cylindrical body, a swinging sliding conical actuating member outside said cylindrical body also provided with a flange, the respective flanges being provided with oppositely disposed recesses, balls located in the said recesses, the flange on the actuating member and the balls acting as a wedge on a swinging of the said actuating member and transferring the said movement to a longitudinal movement of the cylindrical body and the detonating needle, an annular weight on the said actuating member, and a spring normally not under compression for normally holding the said weight in position tight to the actuating member.

9. In a grenade, the combination of a central tube throughout the length of the grenade, a cylindrical body slideable on said tube and provided with a flange, a spring for normally maintaining the cylindrical body in a position of safety, a detonating needle operatively associated with the cylindrical body, a conical swinging and sliding actuating member outside said cylindrical body also provided with a flange, the respective flanges being provided with oppositely disposed recesses, balls located in the said recesses, the flange on the actuating member and the balls acting as a wedge on a swinging movement of the actuating member and transferring the said movement to a longitudinal movement of the cylindrical body and the detonating needle, an annular weight on the said actuating member, and a spring normally not under compression for normally holding the said weight in position tight to the actuating member.

10. In a grenade, the combination of a central tube throughout the length of the grenade, a cylindrical body slideable on said tube and provided with a flange, a conical actuating member outside the cylindrical body lon-

weight on the said actuating member, a spring normally not under compression for normally holding the said weight in position tight to the actuating member, a pointed safety pin pressed against a bevelled edge on the cylindrical body, and a removable plate for normally maintaining the said contact.

10. In a grenade, the combination of a central tube throughout the length of the grenade, a cylindrical body slidable on said tube and provided with a flange, a spring for normally maintaining the cylindrical body in a position of safety, a detonating needle operatively associated with the cylindrical body, a conical swinging and sliding actuating member outside said cylindrical body also provided with a flange, the respective flanges being provided with oppositely disposed recesses, balls located in the said recesses, the flange on the actuating member and the balls acting as a wedge on a swinging movement of the actuating member and transferring the said movement to a longitudinal movement of the cylindrical body and the detonating needle, an annular weight on the said actuating member, a spring normally not under compression for normally holding the said weight in position tight to the actuating member, a pointed safety pin pressed against a bevelled edge on the cylindrical body, a removable plate for normally maintaining the said contact, a percussion cap in proximity to the detonating needle, a detonator in proximity to the detonating needle, an explosive charge in proximity to said detonator, and a casing for the grenade provided with means for attachment to a rifle barrel.

11. In a grenade, the combination of a central tube throughout the length of the grenade, a cylindrical body slidable on said tube and provided with a flange, a spring for normally maintaining the cylindrical body in a position for safety, a detonating needle operatively associated with the cylindrical body, a conical swinging and sliding actuating member outside said cylindrical body also provided with a flange, the respective flanges being provided with oppositely disposed recesses, balls located in the said recesses, the flange on the actuating member and the balls acting as a wedge on a swinging movement of the actuating member and

transferring the said movement to a longitudinal movement of the cylindrical body and the detonating needle, an annular weight on the said actuating member, a spring normally not under compression for normally holding the said weight in position tight to the actuating member, a pointed safety pin pressed against a bevelled edge on the cylindrical body, a removable plate for normally maintaining the said contact, a percussion cap in proximity to the detonating needle, a detonator in proximity to the percussion cap, an explosive charge in proximity to said detonator, and a casing for the grenade provided with means for attachment to a rifle barrel.

12. In a grenade, the combination of a central tube throughout the length of the grenade, a cylindrical body slidable on said tube and provided with a flange, a spring for normally maintaining the cylindrical body in a position of safety, a detonating needle operatively associated with the cylindrical body, a conical swinging and sliding actuating member outside said cylindrical body also provided with a flange, the respective flanges being provided with oppositely disposed recesses, balls located in the said recesses, the flange on the actuating member and the balls acting as a wedge on a swinging movement of the actuating member and transferring the said movement to a longitudinal movement of the cylindrical body and the detonating needle, an annular weight on the said actuating member, a spring normally not under compression for normally holding the said weight in position tight to the actuating member, a pointed safety pin pressed against a bevelled edge on the cylindrical body, a removable plate for normally maintaining the said contact, a percussion cap in proximity to the detonating needle, a detonator in proximity to the percussion cap, an explosive charge in proximity to said detonator, a casing for the grenade with means for attachment to a rifle barrel, and an auxiliary propelling charge carried by the casing.

Signed at Christiania, Norway, this 15th day of January, 1920.

FRIDTJOF NIELSEN BRONDBY.
